UNITED STATES PATENT OFFICE.

CHARLES STEWART FORBES, OF STRATHIDON, SCOTLAND.

CONDENSER.

SPECIFICATION forming part of Letters Patent No. 604,823, dated May 31, 1898.

Application filed November 18, 1897. Serial No. 659,038. (No model.)

To all whom it may concern:

Be it known that I, CHARLES STEWART FORBES, baronet, a subject of the Queen of Great Britain, residing at Castle Newe, Strathdon, in the county of Aberdeen, Scotland, have invented a new and useful Improvement in Condensers, of which the following is a specification.

My invention consists in improvements in condensers employed for dissipating or cooling steam or vapor, the object I have in view being to construct a condenser of larger surface within a much smaller space than heretofore and to enable the same to be easily taken to pieces for cleaning or renewal and rapidly rebuilt.

The construction and operation of my invention will be readily understood by reference to the accompanying drawings, in which—

Figure 1 is a part sectional view of my improved condenser on line A B, Fig. 2. Fig. 2 is a plan. Fig. 3 is an inside view of cover-plate, looking in the direction of arrow, Fig. 2. Fig. 4 is a sectional view of cover having gills. Fig. 5 is a view showing the tie-rod used as a guide. Fig. 6 is a part sectional view showing incased condenser with fan for inducing draft. Fig. 7 is an end view of circular form of condenser. Fig. 8 shows a cruciform piece of gauze or perforated plate. Fig. 9 shows a plate supported by the tie-bolts. Fig. 10 shows air-current induced by steam-jet. Fig. 11 shows air-current induced by connecting to flue. Fig. 12 shows a condenser immersed in water. Fig. 13 shows a perforated metal plate.

In the drawings, 1 represents the end plates or covers. These are preferably made of thin cast or wrought iron, copper, gun-metal, aluminium alloy, or other metal which is a good conductor of heat, and they may be advantageously cast, shaped by pressure, or otherwise formed with gills 2. (See also Fig. 4.) Lugs 3 are formed as shown, and through these tie-bolts 4 are passed and fitted with nuts and washers 5. An inlet-hole 6 is formed in one end plate and an outlet 7 in a suitable position in the other, the exhaust or steam pipe 8 being connected to the inlet 6 and connection made with the hot-well, condensed water tank, or the like by pipe 9.

The inner face of both the end plates or covers is preferably recessed, as at 10, and in this is fitted a thick washer 11, formed of lead, pewter, or other soft metal, or it may be made of rubber, rubber cloth, asbestos, or equivalent compressible or resilient material. Leaves or pieces of perforated metal or gauze 12, formed of copper, plain, tinned, or otherwise coated, aluminium, or other suitable metal, are cut so as to cover or clear the outside edges of the washers, the ends projecting beyond the tie-rods and washers in one or both directions. A washer from one-eighth to one-quarter of an inch or more in thickness is placed between each gauze leaf or perforated sheet, and in order to keep them in position lugs 13, grooved as shown, engage with a special guide-rod 14 on either side, or the washers may be so formed as to engage with the tie-rods, (see Fig. 5,) or the rods may pass through the plates, as in Fig. 9.

It will be readily understood that my invention enables a condenser formed as described to be very readily constructed, as it is merely necessary to add washers and gauze leaves or plates until the required condensing-surface is obtained. The nuts or threaded bolts replacing them are then screwed up until the vessel thus formed is both air and steam tight.

Should grease or other adherent matter be carried into the condenser with the steam and clog the leaves, one or any of them can be quickly removed and cleaned or replaced by simply slackening back the nuts or bolts.

The operation of my invention is as follows: Steam being admitted to the condenser through the inlet 6 encounters the gauze or perforated plate replacing it, which rapidly absorbs the heat and by conduction from within outward dissipates the same, the air circulating through the projecting leaves sufficient to keep the temperature of the plates or leaves comparatively cool. Condensation of the steam is prompt and complete, the condensed vapor trickling down the wires forming the gauze or the plates, as the case may be, further accelerating it. In ordinary positions and at normal temperatures condensation may be satisfactorily effected by the air circulating through the projecting leaves, as described. There are, however, cases in

- which room is an object, or, again, from the surroundings the air may be unduly heated. To meet such cases, I may mount the condenser formed as described in a jacket or 5 casing 15, (see Fig. 6,) air being pulled or blown through by means of a fan 16, or the air may be pulled through by connecting the outlet-port with a flue leading to a stack, (see Fig. 11,) or by a steam-jet, as in Fig. 10, or I 10 may immerse the condenser entirely or partly in water which is or is not cooled artificially, the water being pumped through or over the laminae, as seen in Fig. 12. In Fig. 7 I have shown a condenser of cylindrical shape; but 15 it is obvious that I may modify the shape in several ways to suit varying conditions. The size of mesh employed in constructing gauze condensers is dependent in a measure upon the diameter or area exposed.
- 20 It is desirable that from a constructional point the plates or leaves should be sufficiently stiff to maintain their parallelism under pressure. I have found for small condensers a mesh of twenty to thirty-six to the 25 inch an effective size; but this may be varied considerably either way and still give good results, as the number of pounds of steam condensed by gauze leaves or plates per square foot is largely in excess of that obtained by 30 the most advanced forms of tubular surface condensers, and, as a consequence I can construct most effective apparatus in a very small space.
- What I now claim, and desire to secure by 35 Letters Patent, is—
1. In an apparatus for condensing steam or vapor, the combination with end plates having suitable inlet and exit openings, of pieces of thin, perforated metal separated from each 40 other by packing-rings of yielding material, said pieces being held in position by means of fastening devices passing through the end plates substantially as and for the purpose set forth.
  - 45 2. In a condenser the combination of end plates having respectively an inlet-opening

and an outlet-opening in them, with a series of laminae of conducting material arranged in the intervening space, and adapted to allow the passage of vapor through them, and fastening devices connecting the said laminae to the framing of the said end plates substantially as set forth. 50

3. In a condenser the combination of metallic laminae adapted to allow the passage of vapor through them, packing-rings of yielding material interposed between said laminae, and fastening devices securing the same, with fixed parts of the condenser to which the said fastening devices are attached and which 60 have respectively an inlet and an outlet opening in them, portions of the said laminae being arranged and adapted to project into the refrigerating medium surrounding the condenser substantially as set forth. 65

4. In combination with a condenser having an inlet-opening and an outlet-opening, a series of laminae adapted to allow the passage of vapor through them and arranged between the said openings, means for fastening the said laminae in position, a series of resilient packing-washers interposed between said laminae, and provided with lugs, and guides engaging the said lugs substantially as and for the purpose set forth. 70

5. In a condenser a series of laminae adapted to allow the passage of vapor through them and means for holding them in position, in combination with a casing having an inlet-opening and an outlet-opening and means for supplying refrigerating material to the said casing, the said plates being so arranged that the vapor to be condensed and the refrigerating material will be applied to the same side of the said plates substantially as set forth. 75 80

In testimony whereof I have hereunto set my hand in the presence of two witnesses.

CHARLES STEWART FORBES.
